UNITED STATES PATENT OFFICE.

ALFRED A. LOVEJOY, OF LOWELL, MASSACHUSETTS.

SAFETY GAS-BURNER.

SPECIFICATION forming part of Letters Patent No. 743,007, dated November 3, 1903.

Application filed May 13, 1903. Serial No. 156,954. (No model.)

To all whom it may concern:

Be it known that I, ALFRED A. LOVEJOY, of Lowell, in the county of Middlesex and State of Massachusetts, have invented certain new and useful Improvements in Safety Gas-Burners, of which the following is a specification.

This invention relates to an automatic cut-off for gas-burners, and has for its object to provide a simple and efficient device by which the flow of gas to the burner may be stopped in case the flame is extinguished. The flame may also be extinguished and the flow of gas may be stopped by closing the valve by hand.

My invention is shown in the accompanying drawings, in which—

Figure 1 is an elevation of a front view of a gas-burner with my invention attached. Fig. 2 is an elevation of the same burner as viewed from the right. Fig. 3 is an elevation of a portion of the same burner as viewed from the left with part of the thumb-piece of the cock or valve cut away. Fig. 4 is a part-sectional view from the same point of view as Fig. 1, but with the gas turned off. Fig. 5 is an enlarged sectional view of the pawl and spring shown in Fig. 3. Fig. 6 is a view of the coiled spring and sectional gear shown in Fig. 2. Fig. 7 is a view corresponding to Fig. 1 of a modified form of my device. Fig. 8 shows a view as from the right of Fig. 7. Fig. 9 is a part-sectional view at line X Y of Fig. 7. Fig. 10 is a sectional view of Fig. 7, but with the gas turned off.

Referring to the drawings, A represents a common form of gas-burner, through which runs the passage a from the source of gas-supply.

B is a fish-tail gas-tip.
C is the flame.

D shows a form of valve-stem which passes through a cross-boring in burner A and across passage a. D is cut away at the top and bottom at the point where it crosses passage a, as shown in Fig. 4, so that a turn to the right or left permits the flow of gas to the tip B. Any common form of gas-valve may be used, however. D carries at one end, in such a way that it may be turned thereby, a thumb-piece or key E, by which the gas may be turned on or off by hand. The portion F of the valve-stem D is made smooth and circular in form and is

cut away to form a notch or engaging tooth f, into which a pawl G, pivoted to the burner A at g, may drop, and thereby prevent the valve being turned back after it has been turned beyond a certain point. Pawl G is normally pressed down and against F by the spring-thermostat H. This spring H is shaped somewhat like an interrogation-point and is firmly attached to the top of burner A by means of a collar or by any other suitable means. Spring H thus rises somewhat above the tip B, then curves over and out of the flame C and extends down alongside burner A, as shown in Fig. 4, and ends in the tail h, which is made at an angle to pawl G, and is adapted to pass through a hole or slot x therein, as shown in Fig. 5. Spring-thermostat H is preferably made of strips of two metals which expand unequally, such as brass and steel, as shown at h' and h² in Fig. 5, whereby it tends to straighten when heated and to curl up when cooled. By this construction when the flame is lighted it heats the upper portion of spring H, causing it to expand and tend to straighten, and thus to move tail h away from the burner A, as shown in Fig. 1 and by the dotted lines in Fig. 5. This movement forces tail h through slot x, and by reason of its angular position tail h thus causes pawl G to rise, as shown in Fig. 5. Thus spring H when cold presses pawl G downward and when hot lifts it.

Valve-stem D carries at its end which is opposite to key E a sectional gear K, adapted to rotate said valve-stem and to be rotated thereby. The sectional gear L, pivoted to a projection y on burner A, meshes with gear K and is limited in its movements by projections l l, adapted to strike against K. This sectional gear forms one arm of a lever pivoted at y, the other arm of said lever being M.

N is a spiral-spring thermostat and is attached near the top of burner A to a projection z thereon. This spiral spring N, as will be observed, has more convolutions than spring H, and this fact makes it more sensitive to heat and cold than is H. Spring-thermostat N is also preferably made of strips of two unequally-expanding metals, as shown by n' and n² in Fig. 6, whereby it tends to straighten when heated and to curl up when cooled. The coil of spring N also projects

into flame C, and its tail *n* is passed through an orifice in a ring *m* at the free end of arm M or is connected therewith in any other suitable manner.

- 5 The normal positions of gears L and K and spring N are shown in Figs. 6 and 4, and in the positions there shown valve D is closed, the supply of gas is thus shut off, and there is no flame at the tip B. The tension of spring 10 N when cold is in the direction to keep the parts in the position shown in Fig. 6 by the full lines, and it must be strong enough to close valve D; but when it is heated by flame C it expands, its coil tends to straighten, as 15 shown in Fig. 2 and by the dotted lines in Fig. 6, and its tension is in the opposite direction, therefore tending to keep the valve open, allowing the gas to pass to tip B. The stops *l* and *l*' are adapted to limit the movements of valve-stem D to a quarter-turn of 20 ninety degrees or to such other limited movement as is desired.

The operation is as follows: The thumb-piece E is turned to the right against the pressure of spring N until pawl G is forced into notch *f* by spring H, thus keeping the valve open until the gas is lighted. When the gas is lighted, the heat from flame C causes both springs H and N to expand; but as spring N 25 has more convolutions it expands more rapidly, and when it expands its normal pressure is reversed or neutralized, as explained, and it now holds the valve D open instead of keeping it closed, as it does when cold. The 30 spring H, expanding more slowly, gradually forces tail *h* into its opening *x* in pawl G, thereby lifts G out of notch *f*, and thus leaves valve D free to be turned back except for the pressure of spring N. Now if from any cause, 35 either from its being blown out, air getting into the pipes, or by the gas being shut off at some remote point, the flame C is extinguished both springs H and N begin to cool, contract, and resume their normal positions; but spring 40 N, as explained, having more convolutions, acts more quickly than spring H, and so closes the valve D far enough for notch *f* to pass under the end of pawl G before G can be forced into it, and finally valve D is entirely closed, 45 thus leaving the parts in their original positions with the gas turned off.

Figs. 7, 8, 9, and 10 show a different form of latch device to hold open the cock when the gas is first lighted. Instead of having 50 notch *f* the portion F of key E is smooth. Pawl G is replaced by a semicircular catch P, which is carried at one end by the lower end of spring-thermostat H' and passes around burner A through a guide o. The 55 free end of catch P is bent to form a shoulder *p* and is arranged so that arm M will slide along the outer surface of P against the normal pressure of spring H and be caught and held by shoulder *p* at the point where valve 60 D is open, thus keeping valve D open until catch P and shoulder *p* are withdrawn from contact with arm M. When cold, spring-

thermostat H tends to press catch P toward and against arm M; but when heated its pressure is reversed and carries catch P, and thus shoulder *p*, away from M, thus leaving spring-thermostat N in full control of valve D, as in the first-described construction.

Other kinds of catches operated by the spring-thermostat H will occur to mind where- 75 in the reversing of the tension of the thermostat is utilized to first hold the gas-valve open and to then gradually free it.

In the device shown the tops of springs H and N do not reach far into the flame, but 80 are protruded only into the blue flame at the base near the tip. This arrangement insures a lower degree of heat on the springs and a greater uniformity of temperature. The lower degree of temperature is desirable to 85 prevent the springs being burned out or weakened, as they might be by a high temperature. The springs may be made of brass and steel or of any other suitable metals of 90 unequal expansion.

My invention may be used upon the burners of gas-stoves or upon any other class of burners and with any kind of tip.

The characteristic features of my invention are the use of two spring-thermostats, each 95 of which exerts pressure when cold in one direction and when heated in the opposite direction. One thermostat is adapted to contract and expand more rapidly than the other, and this one is adapted by suitable 100 connections to hold the gas-burner valve closed when cold and open when heated. The other thermostat is adapted to work more slowly and to operate a catch or pawl by forcing it into contact with some of the moving parts connected with the quick thermostat, so as to hold the gas-valve open until 105 said quick thermostat is heated and its direction of pressure is reversed, and after that occurs as the slow thermostat slowly heats it 110 withdraws said catch or pawl, thus leaving the valve free to close, except for the pressure of the quick thermostat. This catch-thermostat also works slowly enough when 115 the gas-flame is extinguished to allow the gas-valve to be closed by the quick thermostat before the catch reaches a position to interfere therewith.

Instead of one thermostat being made with more convolutions than the other, in order 120 to vary their respective speeds in acting, one may be made of heavier or thicker metal than the other, as that one will naturally heat and expand more slowly and cool and contract more slowly than the lighter or thinner 125 one.

What I claim as my invention, and desire to cover by Letters Patent, is—

1. In a safety gas-burner, a cock or valve to regulate the flow of gas, a key or thumb-piece for turning said valve by hand, a sectional gear carried by one end of the stem of said valve, a lever pivoted near its center to the burner and formed with one arm a seg-

mental gear meshing with the first-named segmental gear, combined with a spring-thermostat adapted to throw the other arm of said lever in one direction when the thermostat is cold and in the opposite direction when heated, whereby said valve is controlled by said thermostat.

2. In a safety gas-burner, a cock or valve to regulate the flow of gas, a key for turning said valve by hand, a segmental gear carried by one end of the stem of said valve, a second segmental gear pivoted to the gas-burner, stops at each end of said second gear to limit its movement, an oppositely-extending arm integral with said second segmental gear, a ring carried by and integral with the free end of said arm, combined with a spring-thermostat attached to the top of the burner and adapted to be heated by the gas-flame when lighted and so adjusted that its free end passes through an opening in said ring whereby the valve is controlled by the thermostat.

3. In a safety gas-burner a spring-thermostat part of which is near the tip of the gas-burner and is adapted to exert pressure in one direction when cold and in the opposite direction when heated, a catch carried by the free end of the thermostat and normally adapted to lie yieldingly in the path of one of the attachments of the gas-valve to prevent the gas-valve from being closed after it has been opened, until after the thermostat is heated by the gas-flame and the catch is withdrawn by the expansion of the thermostat, combined with said attachment, a valve, and a key, as described.

4. In a safety gas-burner, a gas-valve, a key thereto, a notch in said key, a pawl adapted to enter said notch when the gas-valve is open, combined with a spring-thermostat adapted to press said pawl into said notch when the thermostat is cold and to lift the pawl therefrom when the thermostat is heated.

5. In a safety gas-burner, a gas-valve, a key thereto, a notch in said key, a pawl adapted to enter said notch when the gas-valve is open, combined with a spring-thermostat attached to the burner near its tip, and a tail or tang at the free end of said thermostat formed at an angle to said pawl, an orifice through said pawl through which said tail passes, whereby when the thermostat is cold it presses said pawl down into and when heated, lifts it from said notch.

6. In a safety gas-burner, a cock or valve adapted to be opened or closed by hand to regulate the flow of gas, a spring-thermostat part of which is close to the gas-flame and is adapted to cause pressure in one direction when cold and in the opposite direction when heated, connecting devices between said thermostat and valve whereby said thermostat

keeps the valve open when the thermostat is heated and rapidly closes it when the thermostat cools, combined with a second thermostat part of which is near the tip of the gas-burner and is adapted when cold to force a catch into position to prevent the gas-valve from being turned back after the gas has been turned on and to slowly release said catch when the flame is lighted and this thermostat is heated, and said catch, as described.

7. In a safety gas-burner, a cock or valve adapted to be opened or closed by hand to regulate the flow of gas, a spring-thermostat part of which is close to the gas-flame and is adapted to cause pressure in one direction when cold and in the opposite direction when heated, and connecting devices between said thermostat and valve whereby said thermostat keeps the valve open when the thermostat is heated and rapidly closes it when the thermostat cools, combined with a notch in the stem of said valve, a pawl adapted to enter said notch when the gas-valve is open, and a spring-thermostat adapted to press said pawl into said notch when this thermostat is cold and to lift the pawl therefrom when this thermostat is heated.

8. In a safety gas-burner, a valve adapted to close and regulate the flow of gas, a quick-acting thermostat adapted to keep said valve closed when cold and open when heated, combined with a slow-acting thermostat adapted to hold said valve open when the gas is first turned on and until the action of the first thermostat is reversed and to then release said valve as described.

9. In a safety gas-burner, a valve D adapted to control the supply of gas, key E adapted to control valve D and provided with a notch f, a pawl G adapted to enter notch f whereby valve D may be held open, slow-acting thermostat H adapted to be actuated by the gas-flame and provided with an inclined tail h adapted to enter an orifice x in pawl G whereby pawl G is raised or lowered, combined with a small sectional gear K carried by valve D, a large sectional gear L adapted to mesh with small sectional gear K and provided with stops l and l to limit its movement, an arm M which is an opposite extension of and integral with gear L pivoted to the burner and carrying bearing m at its free end, and a quick-acting thermostat N provided with tail n adapted to enter an orifice in bearing m whereby valve D is opened and closed as thermostat N is heated or cooled, as described.

In testimony whereof I have affixed my signature in presence of two witnesses.

ALFRED A. LOVEJOY.
